UNITED STATES PATENT OFFICE.

EDWARD H. McCLOUD, OF COLUMBUS, OHIO, ASSIGNOR TO THE KINNEAR MANUFACTURING COMPANY, OF COLUMBUS, OHIO, A CORPORATION OF WEST VIRGINIA.

FOLDING DOOR.

1,278,958.

Specification of Letters Patent. Patented Sept. 17, 1918.

Application filed April 15, 1914. Serial No. 831,945.

To all whom it may concern:

Be it known that I, EDWARD H. McCLOUD, a citizen of the United States, residing at Columbus, in the county of Franklin and 5 State of Ohio, have invented a certain new and useful Improvement in Folding Doors, of which the following is a specification.

This invention relates to that kind of folding door which is divided horizontally 10 into sections the object being to simplify their construction and promote their ease of operation and increase their efficiency.

The invention is embodied in the construction herein shown and described and then 15 pointed out in the claims.

In the accompanying drawings forming part hereof—

Figure 1 is a front elevation of one form 20 of structure containing the invention as viewed from the interior of the building.

Fig. 2 is an edge elevation of the same showing in section the wall in which the door is mounted.

Fig. 3 is a vertical section on the line $x-x$ 25 Fig. 1, and depicting in broken lines an intermediate and the fully raised or open position of the door.

Fig. 4 is a sectional detail on a larger scale showing how the door breaks when the 30 lower section is raised.

Figs. 5, 6 and 7 illustrate sections and a front view of a coupling and hinging member employed in the construction.

Fig. 8 is a detail in horizontal section on 35 the line $y-y$ at Fig. 3 looking down.

Fig. 9 is a similar view on the line $z-z$ Fig. 3 looking in the same direction.

Fig. 10 is a vertical section like that of 40 Fig. 3 of the door showing in connection therewith a plotting of the curve described in operation by the upper edge of the lower section.

Fig. 11 is a front elevation of a modification.

Fig. 12 is an edge elevation of the same, showing in section the wall on which the door is mounted.

Fig. 13 is a vertical section on the line $w-w$ Fig. 11 of the door showing in broken 50 lines an intermediate and the fully raised or open positions of the door.

Fig. 14 is a similar section showing in connection therewith a plotting of the curve described in operation by the upper edge of 55 the lower section.

Referring more particularly to Figs. 1 to 10 the character 20 designates the lower door section and 21 the upper door section. The lower door section is shown as made about twice the height of the upper section. The 60 lower door section is provided at each of its lower corners with a large anti-friction roller 22 that travels on one web of an angle bar 23 that is secured vertically to the adjacent face of a wall 24 that has the door opening 25. Secured on the wall of the building adjacent each angle bar 23 is a short channel 26 and secured on each of the lower corners of the door is a keeper 27 having a bent end that reaches into the channel 26 when the door is lowered to prevent the door from being pushed away from the opening at its lower end.

Secured on each side of the doorway below the line of division between the sections is a bracket 28 having an outwardly inclined groove 28^a and on each side of the lower door section is a pin 29 that projects into said groove when the door is lowered. Said pin can be provided with a small anti-friction roller. The function of the groove 28^a and pin 29 is to project the upper end of the lower door section inward or away from the door opening when that section is raised in the operation of opening the door. 85 This pin 29 can enter a keeper 29^a when the door is lowered to further lock the door against the opening.

The upper door section is hinged at 30 to the building near the upper edge of the 90 doorway. Hinged to a bracket 31 on each lower corner of the upper section is a hinged arm 32 having journaled in its outer end a roller 33 that normally bears upon the inner face of the frame of the lower door section 95 to cause the lower section to draw out the lower portion of the upper door section when the upper portion of the lower section is thrown out by the grooves 28^a. The bracket 31 is provided with two separated bearings 31^a bridged by the hinge 32^a of the arm 32; and on the outer side of the lower door section near the middle horizontal line thereof is a hook 34 in vertical alinement with each of said bridging hinge pins 32^a 100 so that when the lower door section is raised said hooks 34 catch said bridging pins and hingedly connect the sections. The hook 34 has a lateral extension 34^a and the bracket 31 has a matching extension 31^b that laps 105 110

over the extension 34^a when the door is broken or flexed and the sections stand at considerable angles to each other so that these hinging members and the door sections are locked from accidental separation or undue movement with reference to each other in the further operation.

The means shown for raising the lower section (and consequently the upper section) consists of a pair of chains 35 and 35^a connected with the lower corners of the lower door section and running over suitable pulleys to a counter-balance weight 36 that slides in a box vertically secured at one side of the doorway. Small doors might be operated by the application of the hands to the lower door section but with large or heavy doors suitable reducing gearing operating sprocket or pocket wheels for moving appropriate chains 35 and 35^a as suggested in Figs. 1 and 2 can be employed and said gearing and sprocket or pocket wheels operated by a sprocket wheel 36^a and an endless chain 37 running thereover. Such means, however, are common and require no detailed description here.

In the construction illustrated in Figs. 1, 2 and 3 the door, if large, may be raised a part of the way only—as where persons only are to pass under it, but if much head room is desired or required as where loaded vehicles are to pass under the door, the sections are fully raised. In Fig. 3 the door sections are shown by broken lines in the two positions just referred to. In the construction shown in these views the sections when completely raised come foldingly or parallelly together and stand horizontally from the wall. In such horizontal position a support for the outer edge of the projected door may be important. Such a support is shown in Fig. 3 and consists of a bracket 38 fastened to the ceiling or beams thereof and having a seat 38^a to receive suitable casters or rollers 39 secured for this purpose to the edge of the lower door section. As before indicated the path of movement of the upper edge of the door section is illustrated in Fig. 10, said path being indicated by the heavy black line leading from the roller 39.

Referring now to Figs. 11 to 14 inclusive the construction of the door generally is substantially the same as that first described. But the upper door section in the modified construction is provided at its upper edge with brackets 21^a extending upward beyond the door opening each for the reception of the leaf of a hinge 30^a by means of which the upper section is in operative effect made of practically the same height as the lower section. When the lower door section of this modified construction is raised until its lower edge coincides with the top of the doorway or opening, or is in horizontal posi-

tion, the upper door section sustains the outer portion of the lower door section and no additional supporting means such as the bracket 38 is required. A construction like that shown in Fig. 13, however, requires more head room for the installation of the door than a construction like that shown in Fig. 3. In the construction shown in Fig. 13 the hooks 34 are shown as placed nearer the upper edge of the lower door section so that the connection between the two sections is nearer the edge of the lower door section when extended in horizontal position (see broken lines upper portion of Fig. 13) thereby affording a firmer support for the door section when raised to horizontal position. The upper section, of course, braces and amply supports the outer portion of the lower door section in all the substantially elevated positions of that section because of the angular relation of the upper door section to the lower.

The path of movement of the upper edge of the lower door section in the construction shown in Fig. 13 is illustrated by the heavy line leading from said section in the plotting shown in connection with Fig. 14.

The forms of the parts shown can be varied and a part or parts omitted or some parts can be used in conjunction with other and different part or parts without departing from the gist of the invention as finally claimed.

What I claim is:

1. A folding door comprising in combination an upper section and a lower door section suitably mounted to be raised, means on the lower section for hingedly engaging the upper section, the lower door section having a movement independent of the upper door section into and out of hinging engagement, and means on the building independent of the door sections for deflecting the upper portion of the lower section when that section is raised.

2. A folding door comprising in combination an upper section and a lower door section suitably mounted to be raised, means on the lower section for hingedly engaging the upper section, the lower door section having a movement independent of the upper door section into and out of hinging engagement, means on the upper section for holding the lower section toward the upper section when the sections are not hingedly engaged.

3. A folding door comprising in combination an upper section and a lower door section suitably mounted to be raised, means on the lower section for hingedly engaging the upper section, the lower door section having a movement independent of the upper door section into and out of hinging engagement, means on the upper section for holding the lower section toward the upper section when the sections are not hingedly engaged.

engaged, and means in the doorway for deflecting the upper portion of the lower section when that section is raised.

4. A folding door comprising in combination an upper section and a lower door section suitably mounted to be raised, means for hinging the upper door section at its upper edge, the lower door section having a movement independent of the upper door section into and out of hinging engagement, means for temporarily hinged connecting the upper section to the lower section and means whereby both sections are deflected at said connection when the lower section is raised.

5. A folding door comprising in combination, an upper section and a lower door section suitably mounted to be raised, means for hinging the upper door section at its upper edge, means for temporarily hinged connecting the upper section to the lower section, the lower door section having a movement independent of the upper section into and out of hinging engagement, means whereby both sections are deflected at said connection when the lower section is raised and means to prevent the separation of the last named hinging members during the door raising operation.

6. A folding door comprising in combination, an upper section and a lower door section suitably mounted to be raised, means on the upper section for engaging and guiding the lower door section, means on the two sections for temporarily hinging them together when the lower section is raised, means for automatically deflecting the sections where they are hinged together and means for securing the sections against the doorway when the door is closed.

7. A folding door comprising in combination, an upper section and a lower door section suitably mounted to be raised, means on the sections for temporarily hinging them together when the lower section is raised, said means including a hook on one member and a pin to be engaged by the hook on the other, means for guiding the lower section with reference to the upper section and means for deflecting the two sections at the line where hinged together.

8. A folding door comprising in combination, a hinged upper section and a lower door section slidably independently of the upper door section, pivoted means on the upper door section for connecting the lower

door section to it and guiding the same in its upward movement, means on the door frame independent of the door sections for deflecting the lower section when that section is raised and hinging means for connecting the sections after the lower section has been partially raised.

9. A folding door comprising in combination, a hinged upper door section, a sliding lower door section, means for temporarily hinged connecting the two sections when the lower door section is raised, means for causing the deflection of the two sections when the lower section is raised, a channel on the lower portion of the door frame and means on the lower door section for engaging said channel to hold that section against movement from the doorway when the lower door section is lowered.

10. In combination with a door frame, a door having a section adapted to be swung open and closed, a second section adapted to slide upon and swing relative to the first section, means forming a part of the first section for guiding one end of the second section as it slides upon the first section, and stationary means for guiding the opposite end of the second section whereby the second section is adapted to act as a brace to hold the first section open.

11. In combination with spaced guides on opposite sides of an opening, of a closure having a section adapted to be swung open and closed, a second section adapted to have a sliding and swinging movement relative to the first section, means on the first section for guiding one end of the second section in its sliding movement and for causing the first section to be swung open and braced by the second section, the opposite end of the second section being arranged to coöperate with said spaced guides.

12. The combination with two door sections, one hinged to have a swinging motion and means for guiding the other section for sliding into lapped relation to the first named section and into a temporary pivotal engagement therewith, whereby both the sections may be relatively swung and deflected so that the second section shall act to brace the first.

EDWARD H. McCLOUD.
